UNITED STATES PATENT OFFICE.

CHARLES H. HARVEY AND MARMER DUKE ARCHER, OF PHILADELPHIA,
PENNSYLVANIA.

MONKEY-WRENCH.

SPECIFICATION forming part of Letters Patent No. 588,906, dated August 24, 1897.

Application filed February 3, 1897. Serial No. 621,798. (No model.)

To all whom it may concern:

Be it known that we, CHARLES H. HARVEY and MARMER DUKE ARCHER, citizens of the United States, residing at Philadelphia, in the county of Philadelphia and State of Pennsylvania, have invented a new and useful Wrench of the type commonly known as Monkey-Wrench, of which the following is a specification.

Wrenches of this class are usually operated by a thumb-screw under one jaw, requiring the hand of the mechanic or operator to be placed quite close to the jaw and allowing only the strength of the thumb and forefinger to be exerted in forcing the jaws together.

The object of our invention is to enable the full power of the hand and forearm to be exerted in bringing the jaws of the wrench together and to relieve the operator or mechanic from the necessity of thrusting his hand up near the jaw, which sometimes, when the nut to be seized by the jaws is in a contracted space, hole, or narrow slit, is extremely difficult, if not impossible. We attain these objects by the mechanism illustrated in the accompanying drawings, in which—

Figure 1 is a longitudinal section of the head and shank or handle of the wrench. Fig. 2 is the screw which operates the jaw. Fig. 3 is a back view or elevation of the head and shank of the wrench. Figs. 4 and 5 are cross-sections of Fig. 3 at xx and $x'x'$, respectively. Fig. 6 is a longitudinal section of the movable jaw or shell, showing the internally-threaded shoulder. Fig. 7 is a view in perspective of the movable jaw or shell, showing the threaded shoulder with the opening for the entrance of the long screw, Fig. 2. Fig. 8 is a cross-section of the burred cap. Fig. 9 is a vertical section of the same. Fig. 10 is a side view of the complete wrench.

Similar letters refer to similar parts throughout the several views.

A is a hollow shank or handle of the wrench, on which we swage or shrink the head H or cast them in one piece. The handle A is hollowed or channeled from a point near the head for about two-thirds of its length, the channel being of a horseshoe shape in cross-section, the "toe of the shoe," so to speak, being

toward the front of the handle—that is to say, the side on which the jaws project, as shown in Fig. 4, a cross-section of Fig. 3 at xx . Farther away from the head the form of the channel is made of a simple U shape, as shown in Fig. 5, a cross-section of Fig. 3 at $x'x'$.

The face or front of shank A is cut away about one-third of the thickness of the shank, as shown in Fig. 1—that is to say, the cutting extends over the whole of the U-shaped portion of the channel C as deep as the shoulder B in shell S is high. Between the end of the U-shaped portion of channel C and the end of the shank or handle the handle is beveled down on the front, as shown in Fig. 1. The handle and head are bored from end to end at bb in line with the channel, so as to admit the screw R, Fig. 2, the head of which is countersunk in the head of the hammer, as shown in Fig. 1, and the other end of which is extended beyond the length of the handle in order to be inserted in the burred cap D, as shown in Fig. 10.

Fig. 6 is a longitudinal section of shell S, showing the shoulder B extending along the interior of the side of the shell opposite the jaw to a point d as far from the upper face as the upper end d' of channel C is from the hammer-head H. Shoulder B is bored longitudinally and threaded with a left-hand female screw. The shoulder B is cast on the side of shell S opposite the jaw and of an exterior size and form precisely to fit in and fill the horseshoe-shaped portion of channel C, but sliding freely therein.

Fig. 7 is a view in perspective of what we call the "shell" S, which is composed of a hollow casting fitting over the shank and sliding on it, and of the lower or movable jaw of the wrench cast in one piece with the shell, and of shoulder B, just described.

R, Fig. 2, represents a rod of steel somewhat longer than the shank and head of the wrench. It is round and headed at one end, h , and threaded with a left-handed screw for a distance corresponding to the length of channel C. The head h fits into the socket b in the hammer-head H. The other end of R is turned down from the end of the thread d^3 to the diameter of R at the bottom of the thread and

fitted closely in C', the continuation of C. This construction tends to prevent any wab-
bling of R in turning. The end of R from d⁴ is squared, so as to fit into the aperture E in
the burred cap D, and is perforated at I for
the little pin I' to pass through.

The cap D fits on the end of R and covers
the end of the shank A and is formed with a
roughened surface, so as to enable the hand
10 of the operator to take a firm grip. It is of
any size or shape desired, but the central ap-
erture must be squared or shaped, so as to fit
closely on the end of R and turn with it. To
prevent its slipping off, it is fastened by the
15 little pin I'.

To put the shell on the handle, it is pushed
over the beveled end of the shank and on till
the lower face of the shell comes flush with
the lower end of the U-shaped portion of
20 channel C, when the shoulder B can be pushed
up into the channel, and the shell will then
slide along the main portion of the shank A,
the shoulder B fitting into the horseshoe-
shaped portion of channel C and sliding there-
25 in, as before described. Having thus pushed
the shell onto the shank, the rod or screw R
is thrust through the head H and screwed
through the shoulder of the shell till the
square end projects beyond the shank and
30 the head of the screw fits into the countersink
or socket in the head of H. Cap D is then
placed on the squared end of screw R, over
which it fits, so as to come just to the end of
shank A. The small pin or screw I' is then
35 passed through the cap and perforation I in
R. A handle of any description may be
added, covering the shank from the cap D to
the point where shank A is cut away—that

is, where the U-shaped channel meets the
horseshoe shape.

It will be perceived that when the wrench
is thus constructed the jaws will be set by
turning the screw R through shoulder B of
the shell by means of the burred cap D, and
that the cap can be grasped with the full hand
45 and the whole strength of the body exerted
on the screw.

What we claim as new, and desire to secure
by Letters Patent, is—

1. In a monkey-wrench a sliding jaw fitting
50 around a hollow shank or handle and having
an internal core or shoulder fitted to and bearing
upon the interior walls of the shank, sub-
stantially as described.

2. The combination in a monkey-wrench of
55 a hollow shank and a sliding jaw formed to
have a bearing on the outside of the shank
and also on the inside of it, the core of the
jaw being perforated and interiorly threaded
to fit the longitudinal screw, substantially as
60 set forth.

3. In a monkey-wrench the combination of
a hollow handle or shank with a horseshoe-
shaped channel, a close-fitting shell with a
shoulder fitting the hollow of the handle, and
65 a rod running the length of the head and han-
dle and threaded for the length of the chan-
nel, and a cap roughened or burred on the
outside and fitted on the inside to engage and
hold fast the end of the rod or screw, substan-
70 tially as described.

CHAS. H. HARVEY.

MARMER DUKE ARCHIER.
